T. O. SCHRADER

LEVER LOCK FOR REFRIGERATOR DOORS

Filed July 23, 1925

Inventor

Thomas O. Schrader,

By Frederickus & Ferber
Attorneys

UNITED STATES PATENT OFFICE.

THOMAS O. SCHRADER, OF ALLENTOWN, PENNSYLVANIA, ASSIGNOR TO DENT HARDWARE CO., OF FULLERTON, PENNSYLVANIA, A CORPORATION OF PENNSYLVANIA.

LEVER LOCK FOR REFRIGERATOR DOORS.

Application filed July 23, 1925. Serial No 45,538

To all whom it may concern:

Be it known that I, THOMAS O. SCHRADER, a citizen of the United States, residing at Allentown, in the county of Lehigh and 5 State of Pennsylvania, have invented certain new and useful Lever Locks for Refrigerator Doors, of which the following is a specification.

My invention relates to a lever lock for 10 refrigerator and other doors designed to automatically lock the door by slamming and to be released by manual elevations of the lever arm of the lock to cause a cam-like projection of the said arm to ride an 15 inclined surface of the keeper for the said lock and coincidentally of the locking tongue engaging an overhanging part of the said keeper to free the tongue therefrom and thus the door to instantly assume an open 20 position.

To the foregoing ends, my invention consists of a lever lock constructively arranged in substantially the manner hereinafter described and claimed.

25 The nature and scope of my present invention will be more fully understood from the following description taken in connection with the accompanying drawings forming part hereof, in which:

30 Fig. 1, is a perspective of a fragmentary part of a refrigerator door and the jamb of the same, showing in application thereto a lever-lock embodying constructively arranged the main features of my said invention and as shown with the door in a locked condition.

Fig. 2, is an end view of the same.

Fig. 3, is a perspective view of a fragmentary part of a door and the jamb of the 40 same, showing the lever-lock in connection therewith and as shown with the door ajar or in a partially open position.

Fig. 4, is an end view of the keeper with the lever lock in the position it occupies 45 with respect to the said keeper, when the door is ajar or in a partially open position; and

50 Fig. 5, is a perspective view of the rear of the keeper, showing the inner overhanging ledge in detail arrangement thereof.

For the purpose of illustrating my invention I have shown in the accompanying drawings one form thereof which is at present preferred by me, since the same has 55 been found in practice to give satisfactory

and reliable results, although it is to be understood that the various instrumentalities of which my invention consists can be variously arranged and organized and that my invention is not limited to the precise 60 arrangement and organization of the instrumentalities as herein shown and described.

Referring to the drawings: *a* represents a fragmentary part of a door; and *a*¹ the surrounding jamb for the door.

b, is the flat portion of the keeper of the lever lock of my invention secured to the door jamb *a*¹. This keeper is formed with a semi-circular part the lower front edge of which is provided with a cone-like front 70 *b*², terminating in an upper curvilinear cam-like surface *b*³. In the front coned portion of the keeper is provided an overhanging ledge *b*⁴, so that in slamming the door locking the same by the front tongue *c*¹, of the 75 long lever arm *c*, of the lock engaging under the ledge *b*⁴, to thereby instantly hold the door in a closed position.

This lever arm *c*, is also provided with an integral, rear, cam-like projection *c*², arranged to ride the cam-like surface *b*³, of the keeper *b*, through manipulation of the said lever-arm *c*, in an upward direction to release the door from its locked position and thus the door to assume a partially 80 open position, as shown in Fig. 3. The bifurcated part of said lever arm *c*, is pivoted at *d*¹, to a segment-like bearing *d*, the flat base *d*², of which is suitably secured to the door *a*, as clearly shown in Figs. 1 and 3. 85

By a semi-rotary movement of the lever arm *c*, through pressure exerted against the door it is locked, but to bring the door into an absolutely air-tight condition with relation to the jamb *a*¹, this is accomplished by 90 simply exerting a slight downward pressure on the said lever arm *c*, as well as easily and quickly released from such locked position by the elevating of the said lever arm slightly to thus free the front tongue *c*¹, of the 95 said lever arm *c*, from the ledge *b*⁴, of the keeper *b*, as clearly shown in Figs. 3 and 4.

Having thus described my invention, what I claim as new and desire to secure by Letters Patent, is:

A construction of the character stated comprising a housing, a door, a keeper having a flat rear plate secured to said housing and projected forwardly from which is a 110

semi-circular member, the forward upper edge of said member being provided with an inclined cam-like surface and the lower forward edge of said member having extended forwardly therefrom a relatively cone-like formation provided with an inner, overhanging ledge, the outer curved surface of said semi-circular member being continuous and uninterrupted, a lever arm having a bifurcated portion one extension of which is provided with a front tongue and a rear cam-like projection formed integral with said bifurcated portion, a flat

plate secured to said door and provided with a segmental portion which segmental portion is accommodated by said bifurcated portion, a horizontally arranged pivot for connecting said lever and said segmental portion whereby said tongue and rear cam-like projection are respectively arranged to automatically engage the keeper ledge, to lock the door, and to manually permit by riding of said cam-like surface the release of the door from a locked condition. 15 20

THOMAS O. SCHRADER.
